US00D930022S

(12) **United States Design Patent** (10) Patent No.: **US D930,022 S**
 Xie et al. (45) Date of Patent: ** Sep. 7, 2021

(54) **DISPLAY SCREEN OR PORTION THEREOF WITH GRAPHICAL USER INTERFACE FOR INTERACTIVE GUIDELINES FOR MULTIDISCIPLINARY CANCER TREATMENT PLANNING**

(71) Applicant: **Roche Molecular Systems, Inc.**, Pleasanton, CA (US)

(72) Inventors: **Qianwei Xie**, Pleasanton, CA (US); **Marc Mailman**, Pleasanton, CA (US); **Vishakha Sharma**, Pleasanton, CA (US); **Veronica Nemmer**, Pleasanton, CA (US); **Elizabeth Little**, San Jose, CA (US); **Wojciech Kaczmarek**, Pleasanton, CA (US); **Maciej Chmielarski**, Pleasanton, CA (US); **Tomasz Scirurka**, Pleasanton, CA (US); **Szymon Dolata**, Pleasanton, CA (US); **Maciej Laskowski**, Pleasanton, CA (US)

(73) Assignee: **Roche Molecular Systems, Inc.**, Pleasanton, CA (US)

(**) Term: **15 Years**

(21) Appl. No.: **29/709,410**

(22) Filed: **Oct. 14, 2019**

CLAIM

The ornamental design for a display screen or portion thereof with graphical user interface for interactive guidelines for multidisciplinary cancer treatment planning, as shown and described.

DESCRIPTION

FIG. 1 is a front view of first image in the sequence of a display screen or portion thereof with graphical user interface for interactive guidelines for multidisciplinary cancer treatment planning showing our new design;

FIG. 2 is a front view of a second image thereof; and, FIG. 3 is a front view of a third image thereof.

The outermost broken line rectangular indicates a boundary of a display screen or a portion thereof and forms no part of the claimed design. The broken lined text showing the display screen, patterns, and characters form no part of the claimed design. The appearance of the animated images

(Continued)

sequentially transition from FIG. 1 to FIG. 3. The process or period in which one image transitions to another forms no part of the claimed design.

1 Claim, 3 Drawing Sheets
